UNITED STATES PATENT OFFICE

IRVIN W. HUMPHREY, OF WHARTON, NEW JERSEY, ASSIGNOR TO HERCULES POWDER COMPANY, OF WILMINGTON, DELAWARE, A CORPORATION OF DELAWARE

METHOD OF PRODUCING FENCHONE

No Drawing.

Application filed January 14, 1928. Serial No. 246,905.

My invention relates to a method for producing fenchone, and more particularly relates to the production of fenchone by the use of pine oil through the oxidation of fenchyl alcohol contained therein, the pine oil being first fractionated for concentration of the fenchyl alcohol.

The method according to my invention depends upon the discovery that if a pine oil fraction containing fenchyl alcohol be subjected to oxidation, fenchone will be produced through oxidation of the fenchyl alcohol present in the pine oil cut and the fenchone produced may be readily separated from other oxidation products produced due to the fact that the fenchone may be volatilized with steam, whereas the oxidation products of the other pine oil components of the cut are non-volatile with steam. Hence, after the oxidation of the pine oil fraction, the fenchone produced may be readily recovered. Thus, it will be noted that by virtue of my invention the necessity for obtaining fenchyl alcohol substantially pure or in crystalline form before oxidation to fenchone is avoided. This separation involves substantial difficulty due to the solubility of the fenchyl alcohol in pine oil and the nearness of its boiling point to the boiling points of certain other ingredients of the pine oil.

In carrying out the method in accordance with my invention, a pine oil fraction containing fenchyl alcohol is oxidized with nitric acid or with a mixed acid containing nitric acid, as a mixture of nitric acid and sulphuric acid. The nitric acid or the mixture of acids used are diluted with water and may be heated at least initially, to promote oxidation. After the oxidation has started, it may not be necessary to continue the application of heat and since the reaction with nitric acid is preferably carried out at a temperature within about the range 70° C.-99° C. it may be necessary to cool the reaction mixture.

In the carrying out of the method in accordance with my invention, as has been indicated, a pine oil fraction is utilized. For example, pine oil may be fractionated, or, if desired, fractionated and refractionated, to obtain a fraction having a fenchyl alcohol

concentration of say 75% or more. For example, a suitable pine oil fraction may be obtained by fractionating pine oil to obtain a fraction boiling largely between about 196° C. and 207° C. It will be understood that in the carrying out of my method a pine oil cut having a wider boiling range than that indicated as preferable may be used. The boiling range of the pine oil fraction treated, it will be understood, is dictated mainly by considerations of economy.

In carrying out the method in accordance with my invention, using for example, nitric acid, the pine oil cut boiling within about the range 196° C.-205° C. is obtained and say about 160 parts of such cut, which contains about 75% of fenchyl alcohol, is added in the course of about 2½ hours, with agitation, to about 500 parts of dilute nitric acid (20.5% HNO_3). The nitric acid during the addition of the pine oil cut should be heated to a temperature of about 190° F. On completion of the addition of the pine oil cut to the nitric acid, heating is continued for about 3 hours in order to complete the oxidation. On completion of the oxidation, the crude fenchone is separated from the spent acid, treated with an alkaline solution to effect neutralization and then steam distilled from the alkaline solution. A yield of about 85 parts of fenchone will be obtained.

In the carrying out of the method in accordance with my invention with the use of dilute nitric acid, it will be understood that the nitric acid may be used within a wide range of concentration, i. e. 15-40% HNO_3 , but preferably the dilute nitric acid will be of a concentration within about the range 20-35% HNO_3 .

In the carrying out of the method in accordance with my invention where mixed acids are used for the oxidation of a pine oil cut, for example, a pine oil cut boiling within about the range 198° C.-207° C. is obtained and say about 160 parts of such cut is added over a period of about 3 hours, with agitation, to about 700 parts of an acid mixture containing, for example, about 55.1% sulphuric acid, about 14.3% nitric acid and about 30.6% water. During the addition of the pine

oil cut, the acid mixture is held at a temperature of about 85° F. After the completion of the addition of the pine oil cut, the temperature of the acid is raised to about 100° F. and maintained at that temperature for say about 4 hours, in order to insure completion of the oxidation. When the oxidation is complete crude fenchone is separated from the spent acids, treated with an alkaline solution for neutralization and steam distilled from the alkaline solution. A yield of about 80 g. of refined fenchone, boiling point 192° C.-198° C. is obtained, which, if desired, may be further refined by treatment with, for example, alcoholic sodium hydroxide or with aqueous sodium hydroxide. In the use of the mixed acids for oxidation of the pine oil cut, it will be understood that the proportions of acids and water in the mixture may be varied within relatively wide limits. However, the sulphuric acid is preferably present in amounts within about the range 40%-60% and the water, while it may be present in amount less than 30%, is preferably present in amount within about the range 25%-40%.

The fenchone produced by the oxidation of a pine oil cut by the use of nitric acid or mixed acid containing nitric acid, is comparable with fenchone produced by the oxidation of crystalline fenchyl alcohol and, for example, the colloiding action of the product in accordance with the method of my invention, on nitrocotton is, from the practical standpoint as good as that of fenchone derived from crystalline fenchyl alcohol.

It will be noted that in accordance with the method of my invention, fenchone may be produced at a substantial saving of time and expense, since the necessity for obtaining relatively pure or crystalline fenchyl alcohol, and which involves substantial difficulty and expense, is avoided.

It will be understood that when a pine oil cut is used the boiling range of such cut may vary within wide limits, since the selection of the pine oil cut is dictated merely by economy in that where a cut rich in fenchyl alcohol is treated, the yield of fenchone is larger as compared with the yield of other oxidation products than when a pine oil cut poorer in fenchyl alcohol is treated. Hence, the treatment of a cut rich in fenchyl alcohol results in the saving of nitric acid.

In the use of mixed acids according to my invention, sulphuric acid, which acts in a sense catalytically to promote the liberation of nitric oxide, is preferably used with the nitric acid. However, it will be understood that sulphuric acid may be replaced by other mineral acids, as for example, phosphoric acid. Further, in place of nitric acid oxides of nitrogen may be employed as the oxidizing agent in the presence of oxygen and water and it will be further understood that small amounts of a halogen salt, as ferric chloride,

and the like, or an oxygenated salt, as potassium chlorate and the like, may be used and which act catalytically to promote the liberation of oxides from the nitric acid.

It will be understood that in carrying out the method of my invention the degree of concentration of nitric acid used or the proportions of acid and water of the acid mixture and the temperatures, may be varied within wide limits without departing from my invention.

Having now fully described my invention, what I claim and desire to protect by Letters Patent is:-

1. The method of producing fenchone which includes oxidizing a pine oil cut containing fenchyl alcohol with nitric acid and separating fenchone produced from other oxidation products.

2. The method of producing fenchone which includes subjecting a pine oil cut containing fenchyl alcohol to heat in the presence of dilute nitric acid to effect oxidation thereof and separating fenchone produced from other oxidation products.

3. The method of producing fenchone which includes fractionating pine oil to obtain a fraction containing about 75% fenchyl alcohol, subjecting the fraction to oxidation with nitric acid and separating the fenchone produced from other oxidation products by distillation.

4. The method of producing fenchone which includes fractionating pine oil to obtain a fraction boiling within about the range 196° C.-207° C., subjecting the fraction to oxidation with nitric acid and separating the fenchone produced from other oxidation products.

5. The method of producing fenchone which includes fractionating pine oil to obtain a fraction boiling within about the range 196° C.-207° C., subjecting the fraction to heat in the presence of nitric acid and separating the fenchone produced from other oxidation products.

6. The method of producing fenchone which includes fractionating pine oil to obtain a fraction boiling within about the range 196° C.-207° C., subjecting the fraction to heat in the presence of nitric acid of a concentration within about the range 15%-40% and separating the fenchone produced from other oxidation products.

7. The method of producing fenchone which includes oxidizing a pine oil cut containing fenchyl alcohol with a mixture of nitric and sulphuric acids and separating fenchone produced from other oxidation products.

8. The method of producing fenchone which includes fractionating pine oil to obtain a fraction rich in fenchyl alcohol, subjecting the fraction to heat in the presence of a mixture of nitric and sulphuric acids and

separating fenchone produced from other oxidation products.

9. The method of producing fenchone which includes fractionating pine oil to obtain a fraction boiling within about the range 196° C.-207° C., and oxidizing with a mixture of nitric and sulphuric acids and separating fenchone produced from other oxidation products.

10 10. The method of producing fenchone which includes subjecting a pine oil cut rich in fenchyl alcohol to oxidation with a mixture of nitric acid and a mineral acid, and separating fenchone from other oxidation products produced.

11. The method of producing fenchone which includes subjecting a pine oil cut rich in fenchyl alcohol to oxidation with nitric acid in the presence of a substance which acts to promote the liberation of nitric oxide and separating fenchone from other oxidation products produced.

12. The method of producing fenchone which includes subjecting a pine oil cut rich in fenchyl alcohol to oxidation with nitric acid in the presence of a substance which acts catalytically to promote the liberation of nitric oxide and separating fenchone from other oxidation products produced.

13. The method of producing fenchone which includes subjecting a pine oil cut rich in fenchyl alcohol to oxidation with nitric acid in the presence of a mineral acid and separating fenchone from other oxidation products produced.

14. The method of producing fenchone which includes subjecting a pine oil cut rich in fenchyl alcohol to oxidation with an oxidizing mixture including about 55% sulphuric acid, about 14% nitric acid and about 31% water and separating fenchone from other oxidation products produced.

15. A method of producing fenchone which includes oxidizing a pine oil cut containing fenchyl alcohol with nitric acid of a concentration within the range 15%-40% and separating fenchone produced from other oxidation products by distillation.

16. A method of producing fenchone which includes oxidizing a pine oil cut boiling within about the range 196°-207° C. and containing fenchyl alcohol with nitric acid of a concentration within about the range 15%-40% and separating fenchone produced from other oxidation products.

In testimony of which invention, I have hereunto set my hand, at Kenvil, New Jersey, on this 9th day of January, 1928.

IRVIN W. HUMPHREY.
